UNITED STATES PATENT OFFICE.

WALTER T. OXLEY, OF FERGUS FALLS, MINNESOTA.

FILM CLIP.

1,415,189.

Specification of Letters Patent. Patented May 9, 1922.

Application filed December 29, 1919. Serial No. 348,122.

To all whom it may concern:

Be it known that I, WALTER T. OXLEY, a citizen of the United States, residing at Fergus Falls, in the county of Otter Tail 5 and State of Minnesota, have invented certain new and useful Improvements in Film Clips; and I do hereby declare the following to be a full, clear, and exact description of the invention, such as will enable others skilled in the art to which it appertains to 10 make and use the same.

My invention relates to improvements in film clips, and has for its object to provide such a clip that will receive the ends of a 15 looped film and hold the same with its sensitized side out and without touching it at any point to facilitate the developing, fixing, washing and drying of the held film.

To the above end, the invention consists 20 of the novel devices and combinations of devices hereinafter described and defined in the claims.

In the accompanying drawings, which 25 illustrate the invention, like characters indicate like parts throughout the several views.

Referring to the drawings:

Fig. 1 is a perspective view of the improved clip and a film held thereby;

Fig. 2 is a view in section taken substantially on the line 2—2 of Fig. 1; and

Fig. 3 is an elevation of the improved film clip with some parts broken away and sectioned.

The improved film clip comprises a flat 35 U-shaped spring 4 and a transverse tie-plate 5, the latter of which has formed therein two longitudinally spaced slots or openings 6 that are separated by a web 7. The prongs of the spring 4 project through the 40 slots 6 with freedom for movement toward and from each other. To hold the tie-plate 5 against removal from the spring 4, the longitudinal edges of the prongs of said spring are notched at 8 to receive said tie-plate.

Outward of the slots 6, the end portions 45 of the tie-plate 5 extend laterally toward the free ends of the prongs of the spring 4 and in parallel arrangement and co-operation therewith to afford a pair of laterally spaced jaws 9. These jaws 9 are adapted to receive and yieldingly hold the ends of a looped film Z. The free ends of the prongs of the 50 spring 4 extend below the tie-plate 5 in converging relation to afford a pair of fingers 10 for directing the film into the jaws 9.

To assist the jaws in holding a film, the outer members thereof are perforated at 11, and, when said jaws are closed onto the film the gelatine on the outer face thereof will be 55 squeezed into said perforations and assist in holding the same. In some instances, it might be desirable to upset the inner members of the jaws 9 slightly so as to form short barbs which would project into the 60 openings 11 when the jaws are closed.

To apply the improved clip to a film, said film is held loosely looped in one hand, with its sensitized side out, and the clip is held in the other hand with the prongs thereof 70 pressed toward each other to open the jaws 9. When the jaws 9 are open, the prongs of the spring 4 engage the web 7 as a stop to center the tie-plate 5 and thereby causes said jaws to open the same distance. In the 75 open position of the jaws 9, the fingers 10 are brought close together at their ends to form a wedge. With the film and clip thus held, the fingers 10 are inserted between the looped ends of the film Z, which directs the 80 same into the jaws 9. Then by releasing the spring 4, the jaws 9 will yieldingly close onto the film and hold the same without touching throughout its entire length so as to facilitate the developing, fixing, washing 85 and drying thereof. Preferably, the clips will be numbered or otherwise indented so that the operator may keep a record of the films held thereby.

Formed in the sides of the prongs of the 90 spring 4 is a pair of aligned holes 12 adapting the improved clip to be hung on a wire rack or other support.

What I claim is:—

1. A film clip including a spring and a 95 tie-plate having a pair of longitudinally spaced slots through which the prongs of said spring project with freedom for movement toward and from each other, said prongs having notched interlocking engagement with the tie-plate, the ends of the tie-plate being extended into substantially parallel arrangement with said prongs for co-operation therewith to afford a pair of jaws adapted to receive and hold the ends of the 100 film.

2. A film clip including a spring and a tie-plate having a pair of longitudinally spaced slots through which the prongs of said spring project with freedom for movement toward and from each other, said prongs having notched interlocking engage- 105 110

- ment with the tie-plate, the ends of the tie-plate being extended into substantially parallel arrangement with said prongs for co-operation therewith to afford a pair of jaws
5 adapted to receive and hold the ends of the film, the free ends of said prongs being extended outward of the ends of the tie-plate into converging relation to direct the ends of the film into said jaws.
- 10 3. A film clip including a spring and a tie-plate having a pair of longitudinally spaced slots through which the prongs of said spring project with freedom for movement toward and from each other, said
15 prongs having notched interlocking engage-

ment with the tie-plate, the ends of the tie-plate being extended into substantially parallel arrangement with said prongs for co-operation therewith to afford a pair of jaws adapted to receive and hold the ends of said 20 film, and a web in the top of said tie-plate separating said slots and operative as a stop to center said tie-plate and thereby cause said jaws to open equal distances.

In testimony whereof I affix my signature 25 in presence of two witnesses.

WALTER T. OXLEY.
